UNITED STATES PATENT OFFICE.

WILLIAM E. WINE, OF TOLEDO, OHIO.

DOOR ARRANGEMENT FOR RAILWAY CARS.

Application filed November 26, 1921. Serial No. 517,920.

To all whom it may concern:

Be it known that I, WILLIAM E. WINE, a citizen of the United States, residing at Toledo, in the county of Lucas and State of Ohio, have invented certain new and useful Improvements in Door Arrangements for Railway Cars, of which the following is a specification.

This invention pertains to door mechanisms for railway cars or the like, and has among its objects to provide a simple and inexpensive device for supporting and locking the doors in closed positions. Other objects are to provide a self contained device which may be applied to the car as a single unit of manufacture and one in which there shall be a minimum of weight and maximum of efficiency. Also to eliminate in door locking mechanisms the complex winding arrangements that are frequently used, and to which repairs are more frequently necessary than to the present character of device. With such objects in view, the invention consists of the formation, combination and arrangement of parts as will be herein described, and particularly as pointed out in the appended claims.

In the accompanying drawings, which show a preferred embodiment of the invention, Figure 1 is a fragmentary side elevational view of a railway car having a door locking mechanism constructed in accordance with the present invention.

Figure 2 is a fragmentary transverse vertical sectional view through the same, taken approximately on the line 2—2 of Figure 1.

Figure 3 is a similar sectional view taken on the line 3—3 of Figure 1.

Figure 4 is a fragmentary diagrammatical view showing, to a considerably reduced scale, the arrangement of some of the doors upon a car.

Referring now to these drawings, the side of the car is indicated by the reference numeral 1. The numeral 2 denotes the bottom side angle of the car, which is secured to the side 1 of the car by means of rivets 3. The angle 2 is disposed slightly above the lower edge of the side plate 1 and the outstanding leg 4 of this angle is turned toward the inside of the car and forms a ledge beneath which the door may seat, thereby forming a seal to prevent the loss of lading such as coal or the like. The door itself may be formed of a single plate 5 with down-turned side flanges such as 6.

The arrangement of door and car side is such that, as before stated, the plate portion of the door seats beneath the horizontal leg 4 of angle 2, while the down-turned flange 6 of the door plate lies parallel with and just slightly inside of that portion of the car side 1 that extends below the angle 2. The door itself thus lies wholly within the lines of the car sides such as 1, and the door 5 may be hinged to the car floor by co-operating hinges 7 and 8, with hinge pintles 9. The doors, as shown in the drawings, swing parallel with the sides of the car and not transversely of the sides.

The preferred arrangement is that two sets of doors shall be arranged with their remote edges hinged and with the free or swinging edges adjacent to each other, there being preferably down standing flanges 10 formed on the adjacent edges of the doors so as to provide some depth to the space between the free edges of the doors when the same are closed, thereby making it more difficult for material to lose out of this opening in transit.

For supporting the doors, a single supporting bracket 11 is secured to the outer face of the car side 1, some of the rivets 3 being utilized for the securing of this bracket, and there being additional rivets 12 provided for this same purpose, the same being located above the line of rivets 3. The bracket is formed with outstanding lugs or ears 13 arranged in pairs. These lugs are 90 all provided with aligned holes through which is passed in a horizontal direction a pin 14. The pin is held in position by means of cotters 15 which are located between the two central lugs 13, the cotters 95 passing through suitable holes in the pin 14 and being so located as to prevent axial movement of the pin in either direction. Between each of the pairs of lugs 13 is a door supporting hook 16. These hooks are each 100 pierced at their upper extremities and are pivoted upon the pin 14 which passes through the holes in the hooks. One hook is provided for supporting each of the doors and the hooks are arranged to swing transversely of the sides of the car. The hooks are duplicates of each other, with a horizontal door supporting or locking face 17 located somewhat below the pivot point of each hook, and in such positions as to be 110 swung beneath and slightly inside of the lines of the car side when the hooks are in

position for supporting the doors. Each door is provided with an extension which may be formed by riveting a short length 18 of angle iron to the down-standing flange 6 of the door by means of the rivets 19. The angle iron 18 thus constitutes a door-supporting arm which extends outwardly beyond an edge of the door and beneath the down-turned marginal stiffening flange 6.

10 The horizontal leg of this angle is outstanding from the edge of the door and extends outward beneath the car side 1 and slightly outside of the lines of the car side. The locking face 17 of the hook seats beneath the horizontal leg of this angle iron when the doors are closed. Each hook has a suitably inclined approach face 20 for causing the hook to swing back out of the way of the extension 18 when the door is 15 lifted. When the door is fully closed the weight of the hook will cause it to drop into position beneath the angle 18, thereby supporting the door and preventing its release until the hook 16 is forced out of engagement with the door extension.

20

In order to prevent the accidental withdrawal of the hooks and the consequent release of the doors, each hook is provided with a locking cam 21. This cam is set at an acute angle to the line of the car side, so as to conform to the lines of the door hook and rotates at right angles to the direction of swing of the hook. The cam is made in the customary manner with a contacting surface 22 arranged eccentric to the axis of pivoting 23 of the cam, which axis corresponds substantially with the center of the securing pin or rivet 26. The cams are pivoted upon the brackets independently 25 of any other fastenings, there being trunnions 24 formed upon the brackets, these being of suitable form and size to rotatably accommodate the cams 21 and to form pintles therefor. After the cams are slipped over these pintles a washer such as 25 is laid upon the top of the trunnion 24, and the rivet 26 is driven through this washer and through a suitable hole in the center of the trunnion. The rivet 26 does not pass 30 through the car side 1, there being a suitable cavity 27 on the inner face of the bracket 11 to receive the rivet head. Suitable cam seats 28 are formed upon the backs of the hooks 16 against which the eccentric 35 faces 22 of the cams operate.

It will thus be seen that the pair of door locks and cams, together with the attaching bracket, form a self-contained unit which may be manufactured and assembled 40 and then taken to the car plant where the entire mechanism may be applied to the side of the car as a unit without necessitating any co-operative fitting or matching up of parts by the car builder. The rivets 3 and 12 which are used for attaching the

bracket 11 to the car side do not have any function in holding together the various parts of the locking mechanism, so that the car may be constructed in the ordinary manner and the entire mechanism applied 70 after having been correctly gauged and fitted together in a separate plant, especially arranged for this more refined class of work. This is a feature of construction that will be appreciated by those familiar 75 with the art of car-building and car-repairing, where it is extremely desirable that the parts be manufactured and assembled as far as possible in operating units.

I have thus described a preferred embodiment of the present invention. Other embodiments are contemplated within the scope of the appended claims without departing from the spirit of the invention.

What is claimed is:

1. In a door arrangement for railway cars, a pair of doors hinged along their remote edges to the car body and arranged to swing toward each other into closed positions, a bracket attached to the car side near the free edges of the doors, said bracket having a plurality of outstanding lugs with aligned openings therethrough, a door supporting lock for each door, the same being pivoted upon the said bracket between some of the 95 said lugs, there being a single pivot pin disposed through the said aligned openings, the said locks being operable upon the said pin.

2. In a door arrangement for railway cars, the combination with a car having a side, with an inwardly extending ledge slightly above the lower edge thereof, of a door having a plate portion arranged to be seated beneath the said ledge and with a downwardly extending flange beneath the 100 ledge and inside of the lower edge of the car side, a bracket secured to the said door and extending outwardly beneath the lower edge of the car side, a bracket secured to the outer face of the car side, and a door 105 supporting member operatively hinged upon the last mentioned bracket and arranged to be swung transversely of the car side into position beneath the said door bracket, the pivot point of the said supporting member 110 being above the lines of the door and the door supporting face thereof being beneath the lower edge of the car side.

3. In a door arrangement for railway cars, the combination with a car having a side and a floor, of a door hinged in the floor, a bracket secured to the side of the car, a door supporting member hinged upon the bracket and arranged to swing transversely of the car side, and a locking member for 125 the same pivoted upon the said bracket and arranged to be rotated transversely of the plane of operation of the said supporting member.

4. In a door arrangement for railway 130

cars, the combination with a car having a side and a floor, of a door hinged in the floor, a bracket secured to the side of the car, a door supporting member hinged upon 5 the bracket and arranged to swing transversely of the car side, and a locking member for the same pivoted upon the said bracket and arranged to be rotated in a plane at an acute angle with the plane of 10 the car side.

5. A door device for railway cars with hinged doors, including a bracket lying against and affixed to the side of the car near an edge of the door, said bracket having 15 a door-locking member pivoted thereupon, a pin adapted to retain the door-locking member in pivotal relationship with the bracket, said bracket having a recess in its car-contacting face adapted to accommodate 20 the head of the said pin.

6. A door device for railway cars with hinged doors, including a bracket having a base portion lying against the side of the car, means for securing the bracket to the 25 car, the same passing through the base of the bracket and the side plate of the car, a door-locking member pivoted upon the bracket, a pin adapted to retain the door-locking member in pivotal relationship with 30 the bracket, the head thereof lying between the base of the bracket and the car side.

7. A door device for railway cars with hinged doors, including a bracket having a base portion lying against the side of the car, means for securing the bracket to the 35 car, the same passing through the base of the bracket and the side plate of the car, a door-locking member pivoted upon the bracket, a pin adapted to retain the door-locking member in pivotal relationship with 40 the bracket, the said pin passing through the base of the bracket but not through the car side plate.

8. In a door arrangement for railway cars, a door hinged to the car floor, the same having a stiffening flange formed along one of its edges, said flange being turned downward, away from the car floor, a bracket affixed to the door and extending outwardly therefrom beneath the said stiffening flange, 50 and a door-supporting member pivoted upon the side of the car and arranged for supporting engagement with the said bracket.

9. In a door arrangement for railway cars, a door hinged to the car floor, the same having a stiffening flange formed along one of its edges, said flange being turned downward, away from the car floor, a bracket affixed to the door and extending outwardly therefrom beneath the said stiffening flange, 55 and a door-supporting member pivoted upon the side of the car and arranged for supporting engagement with the said bracket, the same having the supporting ledge thereof disposed mediate its length and having 60 the portion below the said ledge formed as an approach plane of a character to cause swinging of the supporting member away from the said bracket upon contact of the bracket therewith when the door is raised. 70

10. In a door arrangement for railway cars, a door hinged to the car floor, the same having a stiffening flange attached to and depending from the lower face thereof, a door-supporting hook pivoted to the car 75 body near an edge of the door adapted to seat beneath the said stiffening flange, the lowermost edge of the said stiffening flange being provided with a local marginal flange 80 in the vicinity of the hook and comprising a hook seat, said local marginal flange lying substantially parallel with the plane of the door and outstanding from the said stiffening flange.

In testimony whereof I affix my signature. 85
WILLIAM E. WINE.
